COIN SLIDE CONSTRUCTION

Mitchell A. Hall, 445 Rossford Ave., Fort Thomas, Ky.
Filed Apr. 13, 1962, Ser. No. 187,298
26 Claims. (Cl. 194—92)

This invention relates to an improved coin slide construction.

An object of the invention is to provide improved and simplified means in a coin slide, for accommodating the device to the use of different coin denominations or sizes without the expenditure of undue labor and skill.

Another object is to provide in connection with a coin slide improved means for the testing of coins or tokens for acceptability or rejection, which means are protected against injury, mutilation, or premature wear when the apparatus is exposed to mischief and abuse.

A further object of the invention is to eliminate the use of delicate and complex parts in a coin slide, with the purpose of reducing manufacturing and assembly costs, and the cost of maintaining the coin slide in properly operative condition.

Another object is to improve the reliability of a coin slide in accepting proper coins or tokens and in rejecting others.

Another object is to greatly facilitate and expedite the substitution of coin slide parts in the field and without resort to expensive factory servicing.

A further object of the invention is to eliminate or at least greatly minimize disability of a coin-controlled machine to render continuous or reliable service due to malfunctioning of the coin-control mechanism associated therewith.

The foregoing and other objects are attained by the means described herein and illustrated upon the accompanying drawings, in which:

FIG. 1 is a top plan view of the improved coin slide, with the slide plate thereof fully retracted.

FIG. 2 is a bottom plan view of the same.

FIG. 3 is a side elevational view taken on line 3—3 of FIG. 1.

FIG. 4 is an elevational view of the side opposite to that illustrated by FIG. 3, part being shown in cross-section.

FIG. 5 is an enlarged fragmentary bottom plan view of the coin slide, showing a proper coin partly advanced to undergo caliperizing.

FIG. 6 is a view similar to FIG. 5, showing an undersized rejectable coin or slug undergoing caliperizing.

FIG. 7 is a fragmentary enlarged cross-section taken on line 7—7 of FIG. 1, the slide plate thereof being fully retracted and embracing an acceptable coin.

FIG. 8 is a view similar to FIG. 7, showing the coin partly advanced.

FIG. 9 is a cross-section similar to FIG. 8, showing the coin in a further advanced position.

FIG. 10 is a view similar to FIG. 9, showing the acceptable coin released from the coin slide after having been tested.

FIG. 11 is a cross-section taken on line 11—11 of FIG. 9.

FIG. 12 is a cross-section taken on line 12—12 of FIG. 10.

FIG. 13 is a cross-section taken on line 13—13 of FIG. 5.

FIG. 14 is a cross-section taken on line 14—14 of FIG. 6.

FIG. 15 is a cross-section taken on line 15—15 of FIG. 13.

FIG. 16 is a cross-section taken on line 16—16 of FIG. 14.

2

FIG. 17 is an exploded perspective view of the coin slide, indicating the simplicity of assembly and substitution of parts.

The coin slide of the invention is of the sliding plate type, wherein a recess or well of the slide plate carries a coin through a series of tests and accepts the coin or rejects it, depending upon ability of the coin to pass the tests. A proper coin will permit movement of the slide plate to a fully advanced position, at which position said plate may strike an actuating element of a vending machine, to initiate dispensing of an article or a service. The nature of the vending machine is of no consequence to the present invention, and such machine accordingly is omitted from the accompanying drawings.

The apparatus comprises in general, FIG. 17, a mounting bracket 20 including a face plate 22, a base section 24 detachable from the bracket, a slide plate 26 reciprocable upon the base section, and a latch plate 28 for retaining the parts 24 and 26 in operative relationship upon the mounting bracket. By resorting to a simple unhooking of the latch plate 28, the several parts 20, 24 and 26 may be quickly and easily disassociated one from another, as in FIG. 17, for effecting replacement or substitution of parts, or for making minor repairs or adjustments with ease and dispatch. In this connection, it is to be noted that the disassembly referred to is accomplished without removing the mounting bracket or the face plate from the wall of a cabinet which usually supports it.

The slide plate 26 may be substantially flat, and will have a finger piece or handle 30 at one end whereby the slide plate may be manually reciprocated. The opposite end 32 may perform to initiate a dispensing operation, when fully extended. Intermediate the ends 30 and 32, the slide plate may be provided with a well or aperture 34 adapted to receive a coin or token C placed therein while the slide plate is fully retracted (FIG. 1). The coin or token is to be advanced past the face plate 22 and into the coin testing mechanism, by advancement of the slide plate by means of handle 30 to the right in FIG. 1.

With further reference to FIG. 17, base section 24 is seen to include a forwardly extending integral neck 36, whose upper surface is grooved to provide ribs 38 upon which may glide the slide plate 26 and any coin placed in well 34. About midway between the ends of base section 24, the middle ribs 38 terminate in inclines 40 sloping downwardly to a lower level provided by a stationary floor plate 42 upon which are formed spaced ribs 44 to support a coin descending from the level of ribs 38. Floor plate 42 is fixed relative to base section 24, and terminates in an edge 46 beyond which an advanced coin is projected to drop into a suitable coin collecting compartment below, not shown. The upper wall or platform 48 of the base section beyond plate 42 is coplanar with ribs 38 and serves to support the slide plate 26.

It may here be noted that face plate 22 is apertured cross its width, as at 50, to receive the neck portion 36 of the base section, so that the free end of the neck may be inserted into bracket 20 to the extent that the free end of the neck abuts a stop 52 at the forward end of the bracket. In the inserted position aforesaid, lateral wings 54 of the base section rest within aperture 50 and are flush with the inner surface 56 of the face plate. Opposite sides of the mounting bracket 20 are grooved at 58 to embrace the side edges of neck 36, to prevent tilting of the base section relative to the mounting bracket. The base section is detachably secured in position upon the mounting bracket by means to be described.

Prior to insertion of base section neck 36 into aperture 50, the slide plate 26 is to be placed flatwise atop the base section, over the ribs 38 and the platform 48, with the elongated ratchet slot 60 astride the fixed up-

standing ears 62 carried by the base section. This places the handle 30 near the free end of neck 36, so that the base section with the slide plate overlying it may be inserted as a unit through aperture 50, this being accomplished by tilting the unit to thread the handle 30 and the neck 36 through the aperture. The height of aperture 50 is, of course, gauged to so accept the slide plate assembled upon the base section.

After the assembled slide plate and base section unit is applied to the mounting bracket, with neck 36 embraced by guides 58, the unit is latched against longitudinal dislocation by application of latch plate 28. The latch plate may be in the form of an elongate metallic strip as shown, having at its forward end a pair of extending fingers 64 to enter a pair of sockets 66 in the rear face of the face plate to prevent up-ending of the latch plate at its forward end. Displacement of the latch plate away from the face 56 of the face plate may be avoided by providing the latch plate with an aperture 68 to be hooked over an upright stationary post 70 fixed upon the face plate.

The rear end 72 of the latch plate may be held down on the slide plate 26 by passing a pin 76 through the apertured ears 62 of the base section, with the pin overlying the groove 74 in the end portion of the latch plate. This is best illustrated by FIGS. 1 and 13, wherein the pin is indicated at 76 passing through the ears 62. By merely removing the pin 76, latch plate 28 may be lifted off the post 70 to release the parts 26 and 24 for bodily displacement from the mounting bracket, as suggested by FIG. 17.

Pin 76 serves also to pivotally support a ratchet pawl 78 which is projected downwardly through slot 60 by means of a light spring 80, to engage the ratchet teeth 82 of the coin slide, for preventing improper slide manipulation back and forth after release of the slide following acceptance of a proper coin. This prevents cheating the vending machine by repeated actuation of the slide on one coin deposit.

If desired, the pin 76 may be temporarily fixed against accidental displacement from the ears 62, by bending against the head of the pin a thin lug 84 provided on the rear end of the latch plate (FIG. 1). The character 86 indicates a permanent magnet fixed to the latch plate, for intercepting ferrous metal slugs deposited in the slide plate in an effort to cheat the dispensing machine.

The character 88 indicates an interceptor for slugs in the form of washers, and includes a depending finger 90 projectable by means of spring 92 to enter the hole of a washer slug advanced by the slide plate, and thereby stop advancement thereof. Interceptor 88 may be pivoted as at 94 upon a side of the latch plate 28, FIG. 7. The finger 90 bears yieldingly atop any coin or slug advanced by the slide plate, and when no coin or slug is present, the finger falls into the coin slide well 34 and thereby performs to limit advancement of the slide plate.

A coin-caliper means is provided, for effecting the rejection of coins or slugs of improper thickness or diameter, and for precluding full slide plate advancement on that account. The coin-caliper means is assembled wholly within the base section 24, and may therefore be replaced by another by the simple expedient of base section substitutions if desired. Thus, a base section equipped with caliper means for one denomination of coin may be quickly and accurately replaced with a similar base section equipped with caliper means for coins of another denomination, all as previously explained in connection with FIG. 17.

The coin-caliper means, FIGS. 2, 5 and 6, comprises a caliper arm 96 having ends 98 and 100, and an intermediate pivot 102 whereby the arm is mounted upon the underside of the floor plate 42 for rocking movement in a plane parallel to said plate. The arm is yieldingly biased with its sweep end 98 directed laterally away from the major axis of base section 24, this being accomplished

by means of a tension spring 104 stretched between the arm end 100 and a stationary post 106 fixed upon floor plate 42. Arm end 98 may be limited in its outward movement, by contact with the base section at 108, FIG. 5. Under certain conditions about to be explained, arm end 98 may sweep toward the major axis of base section 24, in a plane parallel to the mean plane of the base section.

Referring to FIGS. 5, 6 and 11, a stationary caliper shoe is indicated at 110 mounted upon the base section 24. The shoe includes a V-groove 112 in which may slide the edge of a coin advanced by slide plate 26. As will be understood, a thin coin will enter groove 112 somewhat farther than will a thicker coin.

Directly opposite the stationary caliper shoe 110 is located a movable caliper shoe 114, having a pivotal mounting 116 upon the base section. Shoe 114 is movable in the plane of coin C, and has a V-groove 118 therein in which the coin C may slide while advanced by the slide plate 26.

Comparing FIGS. 5 and 6, it will be observed that the genuine or acceptable coin C of FIG. 5, passing between the shoes 110 and 114, moves shoe 114 a greater distance about its pivot 116 than does the undersize coin of FIG. 6. This same result prevails if the coins are of equal diameter, but with the coin of FIG. 6 reduced in thickness.

Movements of shoe 114 are translated to caliper arm 96 through the agency of an extending lug 120 on the arm, located in the path of movement of shoe 114. In FIG. 5, shoe 114 has moved lug 120 to shift the caliper arm 96 toward the major axis of base section 24, whereas in FIG. 6 the coin, being undersize, has failed to move the shoe 114 and arm 96. As will be explained, slide plate 26 will be latched against full advancement unless coin C is properly dimensioned as to diameter and thickness, to shift the sweep end 98 of the caliper arm a certain distance toward the major axis of the slide plate, or of the base section 24.

The aforesaid latching of slide plate 26 against full advancement is performed by a latch element 122 (FIG. 16), pivoted upon the base section at 124 so that the nose 126 of the latch element may move into engagement with an abutment edge 128 of slide plate 26. A spring 130 yieldingly urges the latch element always toward the slide plate, so that whenever the slide plate is advanced longitudinally to bring edge 128 into register with the nose 126 of the pivoted latch element, the nose will tend to assume the latched position of FIG. 16, unless the latch element is restrained from so moving into the path of advancement of abutment 128. FIG. 15 shows the latch element so held in restraint by the end 98 of caliper arm 96, permitting slide plate 26 to advance to the left without interference from latch element 122. The character 97 indicates a stool on the caliper arm adapted to glide upon the underface of base section 24 to stabilize and preclude flexing of the arm.

With reference to FIGS. 14 and 15, the latch element 122 is seen to carry an extension 132 terminating in a crowned ledge or keeper 134 projecting in the same general direction as the nose end of the latch element. This ledge or keeper 134 is situated so that the sweep end 98 (FIG. 14) of the caliper arm may move laterally onto the crowned ledge, as in FIG. 15, to restrain upward movement of the latch element into the path of slide plate abutment 128. Accordingly, when the sweep end 98 of the caliper arm is moved onto ledge 134 as in FIGS. 15 and 5, the slide plate 26 is free to move longitudinally to the fully advanced position for initiating action of a dispenser controlled thereby.

From the foregoing it will be apparent that the coin C of FIG. 5, being a coin of proper diameter and thickness, will effect movement of the caliper arm to the position of FIGS. 5 and 15, at which the slide plate carrying the coin is permitted full advancement without interference from latch element 122. On the other hand, if the coin of FIG. 6 is improper as to diameter or thickness,

the sweep end 98 of the caliper arm will fail to rest upon the crown of ledge 134, and will therefore fail to restrain the latch element, resulting in the condition of FIG. 16 at which the slide plate 26 is latched against full advancement.

It should here be noted that the sweep end 98 of the caliper arm may, depending upon the nature of the disability of the unacceptable coin, either fail to move far enough to mount the ledge 134, or move too far and thereby override the ledge, in either case failing to restrain the latch element from stopping the slide plate.

As in most coin slide devices of the general character herein disclosed, the coin-respective slide plate 26 carries a pair of depending coin pushers 136 and 138 (FIGS. 6 and 7), enforcing movement of the coin with the slide plate in two directions and on both levels 38 and 44 of the base section illustrated by FIG. 17.

With further reference to the caliper means and latch element 122, attention is directed to the fact that no amount of abusive treatment directed to the slide plate can result in transfer of destructive impact to the caliper means, because the full force of any such impact is absorbed directly by latch element 122 while said latch element is out of contact with the caliper arm. The latch element preferably is formed of a very tough and durable material, for example nylon or some other dense plastic material of a suitable character. The base section 24 upon which the latch element is pivotally mounted is, of course, a most rugged constituent of the apparatus and will withstand excessive impact and strain imparted thereto by the latch element.

Directing attention to FIGS. 2, 9 and 10, the character 140 indicates generally a coin ejector the function of which is to project a tested and accepted coin with some degree of force, downwardly and out of the path of coin advancement once it has reached the terminal edge 46 of floor plate 42. The ejector plays a part in preventing cheating the vending machine by reason of an accepted coin hanging in the slide plate aperture 34 and making possible a limited slight reciprocation of the slide plate to obtain repeated vending action on a single coin.

The ejector may be in the form of a bell-crank shape fashioned from strip metal, and having arms 142 and 144 meeting at an angle, the area of meeting being perforated to receive a mounting stud 146 upon which the ejector may rock. An angularly turned lug 148 of arm 142 projects into an opening 150 of floor plate 42, to prevent rotation of the ejector about stud 146.

Arm 144 of the ejector is bent upwardly in substantially parallelism with lug 148, to provide a finger 150 adapted to bear yieldingly against the underface of base section 24 in position to be struck and displaced by an advancing coin, see FIGS. 12 and 11. The finger 150 is normally kept elevated in the path of the advancing coin, by a spring 152 which encircles stud 146 and bears against the pivot area of the ejector arms.

As a coin is advanced by the slide plate, its leading edge strikes the finger 150, and displaces it downwardly from the path of coin advancement. Thereafter, the finger rides upon one face of the coin, the spring 152 pressing the finger against the coin face, FIG. 9, until finally the trailing edge of the advancing coin leaves the finger according to FIG. 10, causing the force of spring 152 to flip the coin and dislodge it from its position upon floor plate 42. Immediately upon dropping of the coin, spring 152 returns finger 150 to the initial position of FIG. 12 in readiness for acting upon a subsequently advancing coin. It may be noted that finger 150 projects through an open slot 154 formed in the terminal edge 46 of floor plate 42.

The device of the invention is highly effective for distinguishing acceptable coins or tokens from those which are unacceptable, and in practice is found to prevent practically every known form of manipulation aimed at

cheating or obtaining free play of a vending machine. The construction whereby movable parts are protected against damage from abusive treatment of the coin slide is especially meritorious, both from the standpoint of expense of maintenance, and reliability of continuous service. Noteworthy also is the disclosed method of assembly whereby substitution or replacement of constituent parts is greatly expedited and simplified, with substantial savings of time and skilled labor.

In conclusion, it should be noted that the caliper shoes indicated at 110 are subject to easy replacement with shoes of different sizes, thereby to adapt the coin slide quickly and inexpensively for the accommodation of coins of different denominations; or, if preferred, the entire base section of FIG. 17 may be quickly and easily removed for substitution with one embracing caliper shoe gauged to the coin denomination desired. The slide plate 26 likewise is easily replaced with one having a coin aperture of the required size.

It is to be understood that various modifications and changes may be made in the structural details of the device, within the scope of the appended claims, without departing from the spirit of the invention.

What is claimed is:

1. A coin slide construction comprising in combination, a mounting bracket including an aperture face plate and an elongate guide means integral therewith and extending outwardly therefrom and aligned with the face plate aperture, a detachable elongate base section having a neck receivable in said aperture and in said guide means, and side portions on said neck to be embraced and supported by said guide means, a slide plate reciprocable upon the base section and having a well to receive a coin for advancement along the base section, an elongate latch plate separate from the base section and the slide plate, and adapted to be superposed upon the slide plate, disengageable cooperative means on the latch plate and the mounting bracket for precluding shifting of the latch plate relative to the mounting bracket upon reciprocation of the slide plate, and means detachably securing an end of the latch plate to the base section with the slide plate interposed between the latch plate and the base section.
2. The combination as set forth in claim 1, wherein the height of the face plate aperture is gauged for passing the combined thicknesses of the slide plate and the neck of the base section through said aperture.
3. A coin slide construction comprising in combination, a mounting bracket including an apertured face plate having a forward side and an elongate guide means integral therewith and extending outwardly from said forward side thereof and aligned with the face plate aperture, a detachable elongate base section having a relatively long transversely reduced width neck portion receivable in said aperture, and side portions on said neck portion to be embraced by said guide means, a slide plate reciprocable upon the base section and having a well to receive a coin for advancement along the base section, an elongate latch plate separate from and of materially less width than the base section and the slide plate, and superposed upon the slide plate, and readily releasable means detachably securing an end of the latch plate to the base section for precluding shifting of the latch plate with the reciprocable slide plate.
4. The combination as set forth in claim 3, wherein the face plate aperture is dimensioned for passing the said reduced portion of the neck of the base section with the slide plate superposed thereon, through said aperture.
5. A coin slide construction comprising in combination, a mounting bracket including an apertured face plate having a forward side and an elongate guide means aligned with the face plate aperture and projecting forwardly from said side of the face plate, a detachable elongate base section having a forwardly extending neck slidably received in said aperture, said neck having side

portions slidably engaging the guide means of the mounting bracket, an elongate coin advancing slide plate reciprocable upon the base section for sliding a coin lengthwise upon the base section, means for detachably securing the base section to the mounting bracket against relative movement, and coin thickness and diameter caliper means supported wholly upon the detachable base section for testing a coin advanced thereto by the slide plate.

6. The device as set forth in claim 5, wherein the combination includes a shiftable latch element carried by the base section and controlled by said caliper means, to latch the slide plate against full advancement along the base section upon failure of the coin to satisfy conditions imposed by the caliper means.

7. A coin slide construction comprising in combination, an elongate base section, and an elongate slide plate reciprocable, upon the base section, said slide plate having a well therein to receive a coin and advance it lengthwise along the base section, a floor plate fixed to the base section, means to guide an advancing coin over the floor plate, and means mounted on the floor plate beneath a part of the base section to caliper the coin during said advancement thereof, the floor plate including a rearwardly directed terminal edge beyond which the coin is advanced by the slide plate, and means supported by the floor plate near the said rearwardly directed edge of the floor plate operative to forcibly flip the coin across the terminal edge of the floor plate and thereby positively disassociate the coin from the base section.

8. The device as set forth in claim 7, wherein the means last mentioned includes a coin-contacting finger, and a spring applying force to press the finger laterally upon one face of the coin in a direction tending to elevate the coin, so that the trailing edge of the advancing coin is flipped as the coin passes beyond the terminal edge of the floor plate.

9. A coin slide construction comprising in combination, an elongate base section having a forward portion and a rearward portion and an elongate slide plate resting upon the top of and reciprocable upon the said portions of said base section, said slide plate having a well therein to receive and advance a coin lengthwise of and on the top of the said forward portion of the base section, a pusher depending from the slide plate to abut one edge of the coin, means on the base section to guide the advancing coin from the top of said forward portion rearwardly to an elevation lower than the slide plate well and below the plane of said rear portion, a floor plate extending rearwardly from said forward portion parallel with the slide plate and at a lower elevation than the plane of the slide plate, said floor plate having a rear edge and having spaced, parallel and longitudinally extending ribs onto which the coin is lowered to be moved therealong and off of said rear edge by said depending pusher positioned between said ribs, a pivoted finger directed downwardly upon the slide plate and adapted to enter the well of the slide plate when the latter is partly advanced, and means constantly urging said finger yieldingly toward the slide plate.

10. The device as set forth in claim 9, wherein the yieldingly urged finger is disposed to ride upon the surface of the coin and bear upon the same at the trailing edge thereof as the latter moves over said guiding means.

11. A coin slide construction comprising in combination, a mounting bracket including an apertured face plate having a front side and an elongate guide means extending forwardly from said front side and aligned with the face plate aperture, a detachable elongate base section having a longitudinally extending neck portion slidably received in said aperture, and side portions on said neck portion to slidably engage the guide means of the mounting bracket, an elongate slide plate supported by and reciprocable upon the base section and having a well to receive a coin for advancement along the base section,

5 an elongate latch plate separate from the base section and the slide plate, and superposed upon and longitudinally of the slide plate, disengageable cooperative means on the latch plate and the base section for detachably securing the latch plate against shifting relative to the base section upon reciprocation of the slide plate, a finger member pivoted upon the latch plate for movement in a plane normal to the plane of slide plate reciprocation, said finger being directed toward and slidably engaging the slide plate to enter the well upon partial advancement of the slide plate, and means constantly urging said finger yieldingly toward the slide plate.

10 12. The device as set forth in claim 11, wherein the combination includes coin diameter and thickness caliper means supported wholly upon the base section exclusive of any connection with the mounting bracket.

15 13. The device as set forth in claim 12, wherein the combination includes a pivoted latch element carried by the base section and controlled by the caliper means, to latch the slide plate against full advancement along the base section upon failure of the coin to satisfy conditions imposed by the caliper means.

20 14. A base section for a coin slide, comprising an elongate flat body formed to provide a longitudinally extending neck portion through approximately half its length and a coplanar, apertured platform portion of greater width than and spaced longitudinally from the neck portion, the said neck portion and the platform portion co-operating to slidably support a reciprocable coin-advancing slide plate, a floor plate fixed upon the base section between the neck portion and the platform portion below and at an elevation beneath the plane of the platform portion, means for guiding a coin downwardly from the level of the extending neck portion to the level of the floor plate, a stationary coin-caliper shoe and a movable coin-caliper shoe spaced apart upon the floor plate to embrace a coin passed therebetween while traversing the floor plate, a caliper arm pivoted upon the floor plate and engageable by the movable shoe for swinging movement about its pivot incident to passage of a coin between said shoes, the caliper arm having a sweep end projecting toward the aperture of the platform portion, a latch element pivoted beneath the platform portion and including a nose extendable through the platform portion aperture to intercept the slide plate, means yieldingly urging said latch element nose into said aperture, and a ledge on the latch element engageable by the sweep end of the caliper arm to oppose the force of said yielding means and preclude extension of the nose through the platform portion aperture, upon passage of an acceptable coin between the caliper shoes.

25 15. The device as set forth in claim 14, wherein the latch element includes a transversely arcuate top surface upon the ledge thereof to be traversed by the sweep end of the caliper arm.

30 16. In a coin slide, a base section including an elongate neck portion and a coplanar apertured platform portion spaced longitudinally therefrom, an elongate reciprocable coin-advancing slide plate shiftable upon the neck portion and the platform portion from a retracted position to a fully advanced position, said slide plate including an abutment, a floor plate fixed to the base section between the neck portion and the platform portion and at an elevation beneath the plane of the platform portion, means separate from the slide plate forming an integral part of the base section for guiding a coin advanced by the slide plate from the top surface level of the extending neck portion to the top surface level of the floor plate, stationary and movable coin-caliper shoes detachably mounted upon the floor plate and spaced apart to embrace a coin moved therebetween by the slide plate, a caliper arm pivoted upon the floor plate and engageable by the movable shoe for swinging movement of said arm about its pivot incident to passage of a coin between said shoes, the caliper arm having a sweep end projecting toward an aperture in the platform

portion, a latch element pivoted beneath the platform portion and including a nose yieldingly extended through the platform portion aperture to intercept the abutment of the slide plate, and means on the latch element engageable by the sweep end of the caliper arm, to hold the latch element in restraint with the nose thereof withdrawn from the path of travel of the slide plate abutment incident to passage of an acceptable coin between the caliper shoes.

17. The device as set forth in claim 16, wherein at least one of the caliper shoes is V-grooved longitudinally where contacted by the advancing coin.

18. A coin slide construction comprising in combination, a mounting bracket, an elongate detachable base section, an elongate reciprocable coin slide plate, slideable longitudinally on the base section, and a connecting means made operative by a single freely withdrawable pin, for detachably holding the mounting bracket, the base section, and the slide plate in assembled readily releasable condition.

19. A coin slide construction comprising in combination, a mounting bracket, an elongate detachable base section supported by the mounting bracket, an elongate coin slide plate supported upon the base section for reciprocation longitudinally, and a latch means including a plate and a selectively displaceable single coupling element between the same and the base section for holding the mounting bracket, the base section, and the slide plate in assembled condition.

20. The combination as set forth in claim 19, wherein is included a coin-caliper means mounted wholly upon the base section when the latter is disassociated from the mounting bracket and the latch plate.

21. A coin slide construction comprising in combination, a mounting bracket including an apertured face plate having a front side and a rear side and an elongate guide means extending forwardly from said front side and aligned with the face plate aperture, an elongate base section having a longitudinally extending forward end neck portion slidably received in said aperture and having side edge portions engaging said guide means of the mounting bracket, the base section having a longitudinally extending rear portion having a top platform surface coplanar with the top surface of said neck portion, an elongate slide plate supported by and reciprocable on the coplanar platform and neck surfaces and having a well for receiving and advancing a coin along said neck surface to and for passage through an opening in the platform surface immediately adjacent to the rear side of the face plate, an elongate latch plate of approximately half the width of the slide plate and base section and disposed longitudinally of and superposed on the slide plate at one side of the approximate longitudinal center of the latter, the latch plate having a longitudinal side portion lying approximately on the longitudinal center of the slide plate, means forming a readily releasable connection between one end of the latch plate and the rear side of the face plate, a readily releasable coupling between the other end of the latch plate and said rear portion of the base section, said releasable means securing the latch plate from longitudinal movement upon reciprocation of the slide plate, the latch plate releasably securing the base section to the face plate, a finger member pivotably mounted upon the latch plate at said longitudinal side portion thereof and slidably engaging the surface of the slide plate to enter the well upon partial advancement of the slide plate, and means constantly urging said finger yieldingly against said slide plate.

22. The invention according to claim 21 wherein the first said releasable means between the said one end of the latch plate and the rear side of the face plate embodies a post carried uprightly upon the rear side of the face plate and an aperture in the said one end of the latch plate and having said post engaged therein and the said one end of the latch plate and the face plate having additional coupling means therebetween for preventing upward displacement of the latch plate from said post.

23. The invention according to claim 21 wherein the first said releasable means between the said one end of the latch plate and the rear side of the face plate embodies a post carried uprightly upon the rear side of the face plate and an aperture in the said one end of the latch plate and having said post engaged therein and the said one end of the latch plate and the face plate having additional coupling means therebetween for preventing upward displacement of the latch plate from said post, and the said readily releasable coupling between the other end 20 of the latch plate and said rear portion of the base section consisting of a pair of upstanding apertured ears on and fixed to the rear part of the said rear portion of the base section and having a rear end portion of the latch plate positioned therebetween, and a pin member extending 25 transversely through said ears and overlying the said rear end portion of the latch plate.

24. The invention according to claim 21 with a permanent magnet secured to the underside of the latch plate and over the slide plate to intercept ferrous metal bodies 30 passing therebeneath in the well of the slide plate prior to the passage of the well over the said opening in the platform surface.

25. The invention according to claim 9, wherein the rest for the slide plate upon said forward portion comprises spaced, parallel ribs extending longitudinally of the forward portion, and the said means to guide the advancing coin to said lower elevation comprises downwardly and rearwardly sloping inclined terminal extensions of the 40 ribs of said forward portion joining the ribs of said floor plate.

26. A coin slide construction comprising in combination, a mounting bracket, an elongate detachable base section, an elongate reciprocable coin slide plate slideable longitudinally on the base section, and means holding the mounting bracket, the base section and the slide plate in readily disassembled operative connection and comprising a latching plate overlying the slide plate, means forming a relatively loose interengaging coupling between the latching plate and the bracket and other means including a readily, manually removable pin connecting the latching plate with the base section and simultaneously maintaining the said interengaging coupling operative.
